J. B. WALKER

BRAKE RELINER

Filed Nov. 13, 1925.

UNITED STATES PATENT OFFICE.

JAMES B. WALKER, OF ORANGE, MASSACHUSETTS, ASSIGNOR TO ATHOL MACHINE & FOUNDRY CO., OF ATHOL, MASSACHUSETTS, A CORPORATION OF MASSACHUSETTS.

BRAKE RELINER.

Application filed November 13, 1925. Serial No. 68,742.

This invention relates to apparatus for re-lining brake, transmission and like bands, wherein the lining is positioned within the band, while the band and lining are held under tension on a relatively rotatable anvil against which the fastening rivets may be upset.

My present invention involves certain improvements upon the rotary reliner disclosed in my prior application, Serial No. 6423, filed February 2, 1925, which in turn was an improvement on the liner shown in Letters Patent to Hunt, No. 1,411,858, dated August 24, 1922, to which reference is made as showing the development of the device involved herein.

While satisfactory for bands of standard width, the device of my prior application lacked capacity for adjustment to accommodate bands of varying width. Moreover, in the device of my prior application, the anvil had a tendency to rotate on its axis under the hammer blows which drove home the fastening rivets and unless the band and lining 25 exactly fitted within the space between the peripheral flanges of the anvil, there was a possibility that the band and lining would not be evenly registered with each other throughout their length or breadth.

My present invention avoids these disadvantages while at the same time possessing a capacity for adjustment to accommodate varying widths of bands and linings. According to it, the rotary anvil is axially adjustable with reference to a stationary circular head of the base member, the parts having a telescopic fit one within the other. This permits the effective distance between the peripheral flanges of the head and anvil 35 respectively to be varied according to the width of the band and lining to be riveted. The axial adjustment of the anvil is made against the tension of a coil spring, the normal tendency of which is to urge the anvil 45 towards the stationary head. This makes certain that the band and lining will be continuously and uniformly pressed towards the peripheral flange of the circular head so that the lining and band will be accurately 50 centered relative to each other throughout their entire extent. The anvil is circular and corresponds to the curvature of the brake drum to which the lining and band are to be fitted, so that when the lining and band 55 are applied to the anvil and the band is

tightened by means of a special screw nut with which my device is equipped, the lining will be laid smoothly within the band which itself is accurately circular.

The pressure of the peripheral flange of 60 the anvil on the band lining makes sure that the lining will not overlap the edge of the band so as to bind on the edge of the drum when applied.

With the lining thus clamped within the 65 band both peripherally and circumferentially, and with the tension of the coil spring acting to prevent accidental rotation of the anvil as the rivets are hammered home, all possibility that the lining will become loose 70 in the band or loose between the rivets is avoided as is the possibility of the lining extending beyond the edge of the band. The lining cannot, therefore, buckle within the band and cannot chatter. 75

In addition to these advantages, the time for relining a band is materially shortened and the labor correspondingly reduced as compared with present practice.

The construction and operation of my de- 80 vice, together with a selected embodiment thereof which well illustrates the principles involved and is itself a form found satisfactory in use, is described and shown in the accompanying specification and drawings, 85 and the characteristic features of novelty are particularly pointed out in the appended claims. Throughout the specification and drawings, like reference characters are correspondingly applied, and in the drawings: 90

Fig. 1 is a side elevation of a relining device in accordance with my present invention.

Fig. 2 is an edge view thereof.

Fig. 3 is a plan view.

Fig. 4 a vertical section on the line 4—4 of Fig. 1.

Fig. 5 is a detailed sectional view of my improved screw nut for tensioning the band circumferentially. 100

I have indicated at 1 a stationary base member which is provided with a flat supporting foot 2, adapted to be rigidly fastened to a bench or support and at 3 with an enlarged circular head having a continuous peripheral flange 4 and an axially disposed bearing 5. 105

Set through the bearing 5 and held therein by a lock nut 6 is a bolt 7 which is provided between its ends with a shoulder 8 110

adapted to abut the adjacent face of said bearing. Loosely mounted on the bolt 7 to rotate thereabout as an axis is a circular anvil 9 which is formed to present a continuous bearing surface 10 which is disposed towards and telescopic within the flange of the stationary head, and constituting a truly circular supporting surface for the lining L and band B to be relined.

10 The anvil is formed with an angular peripheral flange 11 surrounding said circular bearing surface 10 and with a bearing 12 for the bolt 7. Coiled about the projecting end of said bolt, between the head 13 thereof and said bearing 12 is a spring 14, the normal tendency of which is to press the rotary anvil towards the stationary head.

Both the head and the anvil are perforated through their web portions as indicated 20 at 15 to lighten the weight, the holes 15 in the rotary anvil having the additional function of serving as finger openings through which the fingers may be introduced to grasp the anvil and draw it axially along the bolt 25 away from the stationary head. This permits various widths of bands and linings to be laid upon the circular supporting surface 10 of the anvil between the peripheral flanges of the head and anvil respectively.

30 As soon as the anvil is released, the coil spring 14 urges it towards the stationary head, thereby clamping the band and lining frictionally between said flanges and holding it against relative movement when the 35 fastening rivets 16 are driven therethrough and upset against said supporting surface 10. In use, the lining is first laid upon the supporting surface 10 and conforms to the circular shape thereof. The band is next 40 applied over the lining and its ends drawn together by means of a special screw member which I have designed to fit the ears 17 of the band.

This screw nut is detailed in Fig. 5 and 45 consists of a female portion or nut 18 which is interiorly threaded to receive the exteriorly threaded screw 19. Both the nut 18 and screw 19 are provided with enlarged 50 circular heads 20 which may be milled or otherwise roughened, if desired, to facilitate their adjustment and which are adapted to be drawn towards each other and against the outer faces of the ears of the band when the band is tensioned. My special screw nut is simply laid through the 55 slotted ears and upon rotation of the screw member thereof, by means of a screw driver the ends of the band are drawn towards each other until the band is put under sufficient tension. This clamps the lining

smoothly within the band against the supporting face of the anvil so that all tendency of the lining to buckle is eliminated.

The continuous pressure against the edges of the band and lining is exerted by 65 the flanges of the anvil and head so that the lining cannot project beyond the edge of the band and constitute an exposed edge which will bind on the edge of the adjoining drum when the band is replaced in the 70 car. The lining and band are now ready to be riveted together. This may be done in the usual manner, but for convenience of use I supply with my device a special punch 20, the active end of which is concaved to 75 conform to the curvature of the rivet head.

This punch is normally carried in a vertically disposed socket 22, formed in the base member 1 just above the bearing 4 thereof, and it may be removed and held in 80 the hand as an ordinary setting punch in driving home the rivets, or under some circumstances may be left in its socket and itself used as an anvil against which the rivets of a band and lining held in the hands 85 may be upset.

What I therefore claim and desire to secure by Letters Patent is:

1. In a brake band liner, a head having a circular flange, a circular anvil rotatably 90 mounted therein and movable axially thereof, and resilient means for urging said anvil into said head.

2. In a brake band liner, a head having a circular flange, a circular anvil rotatably 95 mounted therein and movable axially thereof, a flange on the outer edge of said anvil, resilient means for urging said anvil into said head to clamp the band and to 100 friction the anvil.

3. In a brake band liner, a head having a circular recess and a central bearing axially thereof, a circular anvil rotatably mounted on said bearing and slidable thereon to fit within said recess and having an outer flange opposed to said recess edge, and a spring disposed to urge said anvil 105 within said recess.

4. In a brake band liner, a head having a circular recess and a headed central bearing axially thereof, a circular anvil rotatably mounted on said bearing and slidable thereon to fit within said recess and having an outer flange opposed to said recess edge, and a spring on said bearing disposed between its head and the anvil to urge said anvil within said recess.

In testimony whereof I affix my signature.

JAMES B. WALKER.
